UNITED STATES PATENT OFFICE

152,320

DESIGN FOR AN AUTOMOBILE

Gordon M. Buehrig, South Bend, Ind., assignor
to The Tasco Corporation, Hartford, Conn., a
corporation of Connecticut

Application November 16, 1946, Serial No. 134,833

Term of patent 3½ years

(Cl. D14—3)

To all whom it may concern:

Be it known that I, Gordon M. Buehrig, a citizen of the United States, residing at South Bend, in the county of St. Joseph and State of Indiana, have invented a new, original, and ornamental Design for an Automobile, of which the following is a specification, reference being had to the accompanying drawing, forming a part thereof, in which:

Fig. 1 is a side elevational view of an automobile embodying my new design;

Fig. 2 is a top plan view thereof;

Fig. 3 is a front elevational view; and

Figs. 4 and 5 are reduced perspective views thereof.

I claim:

The ornamental design for an automobile, as shown.

GORDON M. BUEHRIG.
